US0D1053428S

(12) United States Design Patent (10) Patent No.: US D1,053,428 S
(45) Date of Patent:  Dec. 3, 2024

(54) TABLE LAMP

(71) Applicant: Lingli Chen, Guangdong (CN)

(72) Inventor: Lingli Chen, Guangdong (CN)

() Term: 15 Years

(21) Appl. No.: 29/944,546

(22) Filed: May 29, 2024

(51) LOC (14) Cl. 25-05

(52) U.S. Cl.

USPC D26/104; D26/63

(57) CLAIM

The ornamental design for a table lamp as shown and described.

DESCRIPTION

FIG. 1 is a front, right and top perspective view of a table lamp, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the table lamp that form no part of the claimed design.

1 Claim, 8 Drawing Sheets
